CLAIM

We claim the ornamental design for a display screen of a communication terminal with a user interface, as shown and described.

DESCRIPTION

The FIGURE is a front view of an embodiment of a display screen of a communications terminal with a user interface showing our new design.

The broken line showings of the display screen of a communications terminal and various elements of the user interface are included for the purpose of illustrating environmental structure and unclaimed portions of the display screen of a communications terminal with a user interface and form no part of the claimed design.
